SCRAPER

Charles Le Bleu, Los Angeles, Calif.

Application February 6, 1939, Serial No. 254,851

14 Claims. (Cl. 37—126)

This invention relates generally to material digging, scraping, leveling and transporting machines for use in leveling ground, building and maintaining roads, excavating, grading and transporting materials, and particularly to that class of material handling machines commonly known as "scrapers" by means of which material may be scraped up and moved, and is an improvement upon my co-pending application, Serial No. 756,492, filed December 7, 1934, now Patent No. 2,152,700, in which I disclose a frame carrying a blade and a bowl, said bowl being swingable relative to the frame and blade to dump the load rearwardly of the blade, and it is to be noted that the bowl is closed at its rear end and the material must be dumped through the intake opening, and furthermore, the bottom of the bowl inclines upwardly to a considerable degree toward its rear end so that oncoming material must be forced up a sharp incline during the loading operation, which fact requires a greater pulling force to load the bowl than would be the case if the bottom were disposed in a substantially horizontal position during the loading operation. The fact that the bowl is closed on all sides except at the intake opening is also a disadvantage since the material becomes packed to the extent that it is difficult to dump the load. This invention is also an improvement upon my co-pending application, Serial No. 200,919, filed April 8, 1938, now Patent No. 2,223,829, in which I disclose a bowl support having ground wheels swingably mounted on the rear end thereof, an upstanding arm disposed forwardly thereof, and upon which the forward end of said bowl support is mounted for vertical movement relative thereto, a plurality of vertically spaced sheaves mounted on said post and a cable attached at an end to said bowl support and passing thence about said sheaves to a connection with said swingably mounted ground wheels behind said bowl support, and one of the objects of this invention is to simplify the above structure by eliminating said plurality of sheaves on the upstanding arm, and anchoring the cable to the upstanding arm rather than to the bowl support as shown in the above mentioned application.

Another object of this invention is the provision of a frame, a scraper blade supported on said frame, a bottom movably supported behind said scraper blade in a position to receive material scraped up thereby, said bottom being in substantially a horizontal position during the loading operation, and means for moving said bottom relative to said frame and blade to dump the load behind said blade.

Another object of this invention is the provision of a frame, earth-scraping means supported on said frame, a bowl movably supported behind said earth-scraping means in a position to re-

ceive material scraped up thereby, said bowl being adapted to receive material through its front end and discharge material through its rear end, and means applied to said bowl to cause the same to move relative to said frame and said earth-scraping means to discharge its load behind said earth-scraping means.

Still another object of this invention is the provision of a main bowl, an auxiliary bowl in front of said main bowl and arranged relative thereto to serve as a closure for the front end of said main bowl, both bowls being adapted to discharge material directly onto the ground at their rear ends.

Still another object of my invention is the provision of a main bowl, an auxiliary bowl in front of said main bowl and arranged relative thereto to be loaded in conjunction with said main bowl, both bowls being adapted to discharge material directly onto the ground at their rear ends.

Another object of my invention is the provision of improvements in supports for scraper blades.

Still another object of this invention is the provision of downwardly curved earth scraping means and an earth supporting bottom behind said earth-scraping means to receive earth scraped up thereby, said bottom being curved to conform substantially to the curvature of said downwardly curved earth-scraping means.

Still other objects, features, and advantages of my invention will be apparent to those skilled in the art upon detailed perusal of the attached drawings and the following specifications, wherein I exemplify and describe a preferred embodiment of my invention, but it is to be understood that my invention as herein exemplified and described is susceptible to modification in the combination, correlation and construction of parts, members, and features, without departing from the spirit of my invention as defined in the annexed claims.

In the drawings:

Figure 1 is a top plan view of my invention showing parts in load carrying position.

Figure 2 is a side elevation of my invention showing parts in carrying position.

Figure 3 is a fragmentary side elevation of my invention showing the bowls in dumping position.

Figure 4 is a side elevation in section taken on broken line 4—4 of Figure 1 showing parts in loading position.

Figure 5 is an enlarged top plan view of the auxiliary bowl detached from the machine.

Figure 6 is a fragmentary front view in elevation showing the construction of the blade support.

Figure 7 is a front view in elevation of the main bowl showing the curved bottom.

Referring now more particularly to the drawings, a frame 10 comprises spaced apart parallel side walls 11, rigidly connected by transverse beams 12 and 13, and a transverse scraper support 14, provided with a scraper 14'. Side walls 11 are provided with beams 15, rigid therewith, and converging at their forward ends to a rigid connection with a transverse beam 16. Spaced apart parallel beams 17 are rigid at their rear ends with transverse beam 16 and are provided at their forward ends, on their confronting sides, each with a pair of vertically spaced trunnions 18 upon each of which is journaled a roller 19.

A pony truck 20 is disposed beneath the forward end of parallel beams 17 and is provided with a draft tongue 21 adapted at its forward end as shown for connection to a draft device.

An upstanding arm 22 is disposed between beams 17 adjacent their front ends and is articulately, see Figure 5, mounted at its lower end on, and upstanding from, the pony truck 20, and is provided with grooves 23 extending longitudinally thereof and into which trunnions 18 carrying rollers 19 project. The forward end of frame 10 is thus mounted for up and down movement on upstanding arm 22.

The upper end of said upstanding arm 22 is provided as shown with transversely spaced vertical sheaves 24.

The forward end of frame 10 is provided with transversely spaced brackets 25 carrying a pin 26 upon which are journaled vertical sheaves 27, sheaves 27 and 24 being arranged relative one to the other, and a cable 28 is anchored at 29 and passes thence back and forth about sheaves 24 and 27, and thence, may extend to a winding drum (not shown).

A wheeled truck 30 is disposed rearwardly of frame 10 and is provided with laterally spaced arms 31 pivotally mounted at their forward ends on pins 32 carried by brackets 33, which brackets are rigid with frame 10. Wheeled truck 30 is also provided with transversely spaced upstanding arms 34 rigid at their lower ends therewith, and provided at their upper ends with a pin 35. A roller 36 is disposed between arms 34 and journaled on pin 35. Thus, a rear wheeled truck 30 is mounted on frame 10 for swinging movement relative thereto.

A pair of laterally spaced arms 37 are rigid at their forward ends with frame 10, and are provided at their rear ends with a pin 38. A pulley wheel 39 is disposed between the rear ends of arms 37 and journaled on pin 38.

A pair of laterally spaced brackets 40 are rigid with frame 10 and support a pin 41 upon which is journaled a pulley wheel 42.

Parallel beams 17 support a pin 43 upon which is journaled a pulley wheel 44 as shown.

A tubular member 45 is rigid at its forward end with parallel beams 17 and at its rear end with brackets 40.

A cable 46 passes about roller 36 as shown and both ends of said cable pass thence about pulley wheels 39, 42 and 44, as shown, and both ends are adjustably anchored in a clamp 47 carried by upstanding arm 22, see Figure 4.

It is readily seen that cable 28 may be manipulated to raise and lower the forward end of frame 10, and because of the application of cable 46 to upstanding arms 22 and 34 and its association with frame 10, it is clear that vertical movement of frame 10 on upstanding arm

22 will automatically operate cable 46 to swing wheeled truck 30 and thus cause a similar movement of the rear end of frame 10, and since the mechanical value of arms 31 and 34 is substantially equal, it follows that manipulation of cable 28 will result in raising frame 10 substantially without tilting it.

A back wall 48 is rigid at its ends with side walls 11, and intermediate its ends with transverse beam 12 and brackets 33, and is provided at its lower edge with a spreader blade 49.

Before describing the bowls and their operation, more should be said about scraper support 14, see Figure 6, which comprises a downwardly curved hollow beam 14 as shown and is supported at its ends on side walls 11. A relatively straight rigid member 50 passes through the opening through said beam and is also secured at its ends to side walls 11. A blade 14' is detachably secured to beam 14. The reasons for this construction of beam 14 is as follows; first, the deeper the cut at the center of the blade, the better the dirt moves back into the bowl; secondly, when a blade support fails, it usually bends upwardly between its ends due to a force from below, such as a large rock over which the blade slides thus concentrating the loaded weight of the machine on that portion of the blade in contact with the rock.

A main bowl 51 comprises a bottom 52 and hanger plate 53 disposed one at each side of said bottom and to the lower edge of which said bottom is secured, said hanger plates 53 being pivotally supported on frame 10 at 54 as shown. The main bowl 51 is thus pivotally supported in a position behind said scraper blade to receive material scraped up thereby. Each of the hanger plates 53 is provided with a projection 55 rigid therewith and extending laterally through openings 56 provided in each of the side walls 11, trunnions 55 each having sheave means 57 journaled thereon.

An auxiliary bowl 58 is disposed forwardly of scraper blade 14' and is provided at each of its ends with arms 59 rigid therewith and extending thence upwardly to a pivotal connection with frame 10 at 60, each of said arms being provided intermediate their ends with a pin 61 having journaled thereon, sheave means 62. Thus, the auxiliary bowl 58 is disposed forwardly of the scraper blade 14' and arranged relative thereto to be loaded in conjunction with the main bowl, that is to say, when the main bowl has become loaded, the dirt subsequently scraped up tends to move upwardly and then fall forwardly into the auxiliary bowl.

The following sheaves are journaled upon pins carried by frame 10 as shown, and are located as follows; viewing Figure 2, sheaves 63 are located directly above auxiliary bowl 58; sheaves 64, just above scraper support 14; sheaves 65, on the top side of transverse beam 16; and sheave 66 is located near the lower rear corner of frame 10 and projects through an opening provided in side wall 11. Viewing Figure 3, sheaves 67, 68, and 69 are located above transverse beam 16; sheaves 70 and 71 just rearwardly of transverse beam 16; sheave 72 just above and slightly rearwardly of scraper support 14; sheave 73, is located near the lower rear corner of frame 10 and projects through an opening provided in side wall 11.

Beginning now with Figure 3, a cable 74 is anchored to bowl support 10 at 75, and passes thence back and forth about sheaves 57 and 72

and thence to and about sheave 73, thence to and about sheave 66, see Figure 2, and thence back and forth about sheaves 57 and 64, and thence to sheaves 63, thence back and forth about sheaves 63 and 62, and thence to and about sheave 65, thence transversely of frame 10, see Figure 1, to and about sheave 69, thence rearwardly to sheave 71, thence downwardly to, see Figure 3, and then upwardly about sheave 62, thence to and about sheaves 10, 68 and 67 respectively, and thence over sheave 76 journaled on a pin 77 carried on the forward end of one of the parallel beams 17. Cable 74 may then extend to a winding drum, not shown.

Being in the carrying position of Figure 2, with bowls 51 and 58 loaded, the machine is drawn to the place where the load is to be dumped and a pulling force is applied to cable 74. This will result in first swinging the auxiliary bowl 58 to the position shown in Figure 3, the main bowl 51 remaining in the position shown in Figure 2. But a continued application of the pulling force to cable 74 will then result in swinging the main bowl 51 to the dumping position shown in Figure 3, the material moving out at the rear end of bowl 51 directly onto the ground behind the blade 14'. Thus, cable 74 is applied to both bowls, and a pulling force applied to cable 74 results in dumping the bowls at their rear ends in predetermined order. Being in the dumping position of Figure 3, the material dumped by bowls 51 and 58 may be spread to the desired thickness by proper manipulation of cable 28 to position frame 10, and consequently, spreader blade 49 the desired distance from the ground.

Being in the position of Figure 3, the bowls 51 and 58 may be returned to the position of Figure 2, by releasing cable 74, and the bowls will automatically return by gravity to the position of Figure 2, in which position the machine is drawn to the place where a load is to be gathered.

Being in the position of Figure 2, the machine may be caused to assume the loading position of Figure 4 by again applying a pulling force to cable 74 until bowl 58 has been raised to the position, or a similar one, shown in Figure 4, in which position it may be maintained by cable 74, the bowl 51 remaining in its lowermost position with respect to frame 10. Suitable manipulation of cable 28 may then be had to lower frame 10, and consequently, scraper blade 14' to a scraping contact with the ground as shown in Figure 4, and as the machine moves forward, the scraped up material will be forced rearwardly into the main bowl 51 by the oncoming material until the bowl 51 is loaded, after which the oncoming material will move upwardly against the material in bowl 51 and then fall forwardly into auxiliary bowl 58. When both bowls are loaded, cable 74 is released to allow the auxiliary bowl 58 to close by gravity assisted by the load therein. However, the auxiliary bowl will not, as a rule, completely close until suitable manipulation of cable 28 is had to raise frame 10 and scraper 14' from scraping contact with the ground, and as scraper blade 14' is thus raised the auxiliary bowl 58 will move downwardly with respect to frame 10 resulting in retaining a load in both bowls. Continued suitable manipulation of cable 28 will eventually result in again disposing all parts in the carrying position of Figure 2, except however, that the lower edge of auxiliary bowl 58

may not actually be in close contact with blade 14'; but, practically speaking, will be closed sufficiently to retain a suitable load of material in both bowls.

5 Referring now briefly to Figure 7, it will be noted that the bottom 52 of main bowl 51 is curved downwardly to conform to the curvature of scraper support 14 shown in Figure 6.

From the foregoing description it will be seen that I have exemplified and described such a device as substantially fulfills the objects of my invention as set forth, and what I claim as new and useful and desire to secure by Letters Patent is:

15 1. In a scraper, a frame having spaced apart parallel side walls and means rigidly connecting said side walls, a transverse scraper blade supported on said frame, a bowl including a bottom and hanger plates disposed at each side of said bottom and to which said bottom is secured, means pivotally supporting said hanger plates on said frame so as to support said bottom in loading position behind said scraper blade to receive material scraped up thereby, an opening through each of said side walls, projections carried by said hanger plates in register with said openings, and means applied to said projections for swinging said bowl relative to said frame and blade to dump the material behind said blade, said hanger plates being adapted to close said openings in loading position of said bowl.

2. In a scraper, a frame, a main bottom, an auxiliary bottom disposed forwardly of said main bottom and arranged relative thereto to be loaded in conjunction with said main bottom, both of said bottoms being operably disposed with said frame and adapted to discharge material directly onto the ground at their rear ends, a transverse scraper blade disposed between the confronting ends of said bottoms for scraping up materials for loading the same and means applied to said bottoms to swing the same to separate positions one in front of the other and inclining downwardly at their rear ends so as to dump material from each of said bottoms directly onto the ground at their rear ends, a spreader blade carried by said frame rearwardly of said bottoms for spreading the materials dumped from said bottoms, and means for raising and lowering said frame so as to selectively position said spreader blade relative to the ground thereunder.

3. In a scraper, a wheel supported frame, a transverse scraper blade supported on said frame, a main bowl, means pivotally supporting said main bowl on said frame in a position behind said scraper blade to receive material scraped up thereby, an auxiliary bowl disposed forwardly of said scraper blade and arranged relative thereto to be loaded in conjunction with said main bowl, both bowls being adapted to dump material directly onto the ground at their rear ends, and means applied to said bowls to cause the same to dump in predetermined order.

4. In a scraper, a wheel supported frame, a transverse scraper blade supported on said frame, a main bowl, means pivotally supporting said main bowl in a position behind said scraper blade to receive material scraped up thereby, an auxiliary bowl disposed forwardly of said scraper blade and arranged relative thereto to be loaded in conjunction with said main bowl, both bowls being adapted to dump material directly onto the ground at their rear ends, and means applied to

said bowls to cause the same to dump in reverse order to that first above mentioned.

5. In a scraper, a wheel supported frame, a transverse scraper blade supported on said frame, a main bowl, means pivotally supporting said main bowl in a position behind said scraper blade to receive material scraped up thereby, an auxiliary bowl disposed forwardly of said scraper blade and arranged relative thereto to be loaded in conjunction with said main bowl, both bowls being adapted to dump material directly onto the ground at their rear ends, and a common operating means applied to said bowls to cause the same to dump in a predetermined order.

6. In a scraper, a wheel supported frame, a transverse scraper blade supported on said frame, a main bowl, means pivotally supporting said main bowl in a position behind said scraper blade to receive material scraped up thereby, an auxiliary bowl, means pivotally supporting said auxiliary bowl in a position in front of said scraper blade to be loaded in conjunction with said main bowl, both bowls being adapted to dump material directly onto the ground at their rear ends, and means for swinging said bowls relative to said frame and blade to cause said bowls to dump in predetermined order.

7. In a scraper, a wheel supported frame, a transverse scraper blade supported on said frame, a main bowl, means pivotally supporting said main bowl in a position behind said scraper blade to receive material scraped up thereby, an auxiliary bowl, means pivotally supporting said auxiliary bowl in a position in front of said scraper blade to be loaded in conjunction with said main bowl, both bowls being adapted to dump material directly onto the ground at their rear ends, and means for swinging said bowls relative to said frame and blade to cause said bowls to dump in reverse order to that first above mentioned.

8. In a scraper, a wheel supported frame, a transverse scraper blade supported on said frame, a main bowl, means pivotally supporting said main bowl in a position behind said scraper blade to receive material scraped up thereby, an auxiliary bowl, means pivotally supporting said auxiliary bowl in a position in front of said scraper blade to be loaded in conjunction with said main bowl, both bowls being adapted to dump material directly onto the ground at their rear ends, and a common operating means applied to said bowls for swinging the same relative to said frame and blade to cause said bowls to dump in predetermined order.

9. In a scraper, a frame, a transverse scraper blade supported on said frame, a main bowl, means pivotally supporting said main bowl in a position behind said scraper blade to receive materials scraped up thereby, an auxiliary bowl disposed forwardly of said scraper blade and arranged relative thereto to be loaded in conjunction with said main bowl, both bowls being adapted to dump materials directly onto the ground at their rear ends, and means applied to said bowls for causing the same to dump.

10. In a scraper, a wheel supported frame, a main bowl pivotally supported on said frame, an auxiliary bowl disposed forwardly of said main bowl and confronting the same so as to be loaded in conjunction with said main bowl both bowls being adapted to dump materials directly onto the ground at their rear ends, a scraper blade disposed between the confronting ends of said bowls for scraping up the materials for loading the same, and means applied to said bowls to

cause the same to dump directly onto the ground at their rear ends.

11. In a scraper, a wheel supported frame, a main bowl operably disposed with said frame, an auxiliary bowl disposed forwardly of said main bowl and confronting the same so as to be loaded in conjunction with said main bowl, both bowls being adapted to discharge materials directly onto the ground at their rear ends, a transverse scraper blade arranged between the confronting ends of said bowls for scraping up material for loading the same, a spreader blade carried by said frame rearwardly of said bowls, means applied to said bowls for causing the same to discharge through their rear ends each directly onto the ground forwardly of said spreader blade, and means for raising and lowering said frame so as to selectively position said spreader blade relative to the ground thereunder.

12. In a scraper, a wheel supported frame, a main bowl pivotally supported on said frame, an auxiliary bowl disposed forwardly of said main bowl and confronting the same so as to be loaded in conjunction with said main bowl, both bowls being adapted to dump materials directly onto the ground at their rear ends, a scraper blade disposed between the confronting ends of said bowls for scraping up the materials for loading the same, a spreader blade carried by said frame rearwardly of said bowls, means applied to said bowls to cause the same to dump in predetermined order through their rear ends directly onto the ground forwardly of said spreader blade, and means for raising and lowering said frame so as to selectively position said spreader blade relative to the ground thereunder.

13. In a scraper, a wheel supported frame, a main bowl including a bottom and hanger plates disposed at each side of said bottom and to which said bottom is secured, means pivotally supporting said hanger plates from said frame, an auxiliary bowl disposed forwardly of said main bowl and confronting the same so as to be loaded in conjunction with said main bowl, said auxiliary bowl being provided with rearwardly extending arms pivotally supported on said frame, both bowls being adapted to dump materials directly onto the ground at their rear ends, a scraper blade disposed between the confronting ends of said bowls for scraping up the materials for loading the same, a spreader blade carried by said frame rearwardly of said bowls, means applied to said bowls to cause the same to dump in predetermined order through their rear ends directly onto the ground forwardly of said spreader blade, and means for raising and lowering said frame so as to selectively position said spreader blade relative to the ground thereunder.

14. In a scraper, a frame, a transverse scraper blade supported on said frame, a main bottom swingably supported on said frame behind said scraper blade in position to receive materials scraped up thereby and adapted to dump materials directly onto the ground behind said scraper blade, an auxiliary bottom swingably disposed forwardly of said blade and arranged relative thereto to be loaded in conjunction with said main bottom, said auxiliary bottom being adapted to dump materials directly onto the ground in front of said blade, and means applied to said bottoms to swing the same in predetermined order into their respective dumping positions behind and in front of said blade.
